UNITED STATES PATENT OFFICE.

JOHN O. HEINZE, OF SPRINGFIELD, OHIO, ASSIGNOR TO THE JOHN O. HEINZE COMPANY,
OF SPRINGFIELD, OHIO, A CORPORATION OF OHIO.

STARTING AND LIGHTING SYSTEM.

1,266,682.

Specification of Letters Patent. Patented May 21, 1918.

Application filed March 1, 1916. Serial No. 81,398.

To all whom it may concern:

Be it known that I, JOHN O. HEINZE, a citizen of the United States, residing at Springfield, in the county of Clark and State of Ohio, have invented certain new and useful Improvements in Starting and Lighting Systems, of which the following is a specification.

My invention relates to improvements in starting and lighting systems for automobiles, and it more particularly relates to a system especially adapted for that type of automobile known as the Ford, although features of the system are equally applicable to other machines.

The object of the invention is to provide a system of the character referred to which may be installed as a unit without material alteration in the machine to which it is applied so that the system may be readily installed on machines already in use, by automobile workmen of ordinary skill.

A further object of the invention is to provide a two unit system which has a simple and effective arrangement of driving connections between the starting motor, crank-shaft of the engine and generator.

A further object of the invention is to provide a system of the character referred to which will be simple in its arrangement and effective in its operation.

In the accompanying drawings:—

Figure 1 is a front elevation of the support for the operating parts of the system.

Fig. 2 is a side elevation of the same.

Fig. 3 is a front elevation of the support with the operating parts connected therewith shown applied to a machine of the type referred to.

Fig. 4 is a side elevation of the same.

Fig. 5 is a detail in section of the fan connection.

In the construction of my system, I employ a single bracket for supporting the operating parts so formed that it can be readily attached to the machine to which the system is to be applied. In the present case, in which the mechanism is shown applied to a Ford machine, this is accomplished by simply removing from the machine what is known as the casing for the timing gears

and distributor, the front hose connection to the water jacket of the engine, and the fan belt pulley on the crank shaft. The bracket, which is shown in Figs. 1 and 2 and designated generally by the reference character A, is preferably formed on the front and rear with strengthening ribs *a* and *b* respectively. At its upper end is an integrally formed coupling 1 for the flexible connection for the cooling system, this coupling communicating with the water jacket. The lower portion of the support is provided with an integrally formed housing 2 for the timer and in proximity thereto with 65 an integrally formed oil receptacle 3. The reference character 4 represents bolt holes for the reception of bolts for the purpose of securing the support at the same points of attachment for the old distributor and timing gear casing, which is removed and discarded, and the same bolts, represented by 5 in Fig. 3, may be employed for the purpose, these bolts entering the engine casing B. Adjacent the water connection, the 70 bracket is also provided with openings 6 which will coincide with the openings in the engine casing which were formerly employed for securing in place the old coupling and the same bolts 7 may be employed 75 for securing the bracket in place at this point. The lower portion of the bracket is provided with a rounded recess 8 to allow it to fit over the crank shaft and bolt openings 9 formed in a forwardly extending 80 flange 10 along the lower edge of the support provides means for attaching it to the lower half of the engine crank case by bolts 11; this point of attachment being also the same as that for the old discarded gear and 85 distributor casing. The rear side of the bracket has a finished raised face, *c*, to fit the upper portion of the crank casing of the engine. By the construction thus far described it can be seen that this bracket 90 support will be secured in position with no material alteration in the machine to which it is applied, the only change required being simply the discarding of the old casing, 95 hose coupling and belt pulley referred to. Before the bracket is installed, the operating parts are secured in their proper 100

working positions thereon. To the rear of the bracket are secured a motor 13 and generator 14, openings 15 and 16 being formed in the bracket to receive the bearings for the motor and generator shafts 17 and 18. For this purpose the bracket is provided with screwthreaded openings 13^a and 14^a respectively, to receive the ends of screw bolts 13^b and 14^b which are inserted from the rear through the motor and generator casings respectively. Upon the forward portion of the support A is formed a housing 19 and in this housing and secured to the generator shaft is a gear 20, which, when the motor is started, is driven by a pinion 21 from the starting motor shaft. This pinion 21 forms a part of a well-known drive now in general use, the pinion being weighted and threaded upon a screw 22 which is loosely mounted and longitudinally movable upon the motor shaft 17 and revolvably connected therewith through the medium of a collar 24 secured to the motor shaft, a collar 25 secured to the screw, and a coil spring 26 connecting the two collars, as a result of which the screw 22 may be allowed to move along the shaft by placing the spring 26 under tension until the pinion and gear are properly in mesh; it being understood that so soon as the motor starts and the screw thereby revolved the pinion 21 being held from rotating by the weight thereof will ride along the screw until it becomes meshed with the gear and will thereafter rotate with the screw. So soon as the engine starts and the gear 20 becomes the driving element, the pinion will be rotated about the screw, which is now at rest, and thrown out of mesh with the gear.

Secured to the generator shaft in front of the gear 2 is a sprocket wheel 27 (shown in dotted lines in Fig. 3) about which passes a sprocket chain 28 which also passes about a sprocket wheel 29 secured to the engine crank shaft 30 at the point where the old fan belt pulley was formerly placed, this pulley being discarded; this connection forming the means for starting the engine from the motor and also for operating the generator after the engine has started.

Also secured to the generator shaft in front of the sprocket 27 is a pulley 31 about which passes a belt 32 for the purpose of driving the fan 33 which is the same fan that was originally installed, and the same bracket 34 which originally supported it is employed, this bracket being secured in position by one of the bolts 5 previously referred to. Also in order that the fan belt 60 may be located in a different plane from the chain 28, it has become necessary to attach to the fan shaft a separate pulley for the belt. This pulley is shown in detail in Fig. 5 and consists of two portions 35 and 35' 65 which are clamped to the old flat belt pul-

ley, indicated by 36, in such a way that the grooved portion of the new pulley will lie forward of the grooved portion of the old pulley so that the new pulley may be brought in line with the pulley 31 on the generator shaft. An adjusting screw 38 threaded in a forwardly projecting lug 37 and bearing against the bracket 34 furnishes the means for adjusting the tension of the belt 32.

By the construction described, it will be seen that a starting and lighting system for automobiles is provided which is simple in its arrangement and construction and also one which can be installed as a unit; that is, all of the essential operating parts can be mounted on the supporting bracket and made ready for easy and quick installation, and by reason of the fact that these brackets can be secured to the machine at already established points of attachment, this insures the proper relation of the driving parts relative to the crank shaft of the engine and enables the center points of all the driving parts being accurately fixed relative each other so that no unusual adjustment is necessary in installation.

Having thus described my invention, I claim:

1. In a system of the character described, the combination with an automobile engine and its crank shaft, of a main support, said support being provided with points of attachment corresponding to established points of attachment in relation to said engine and its crank shaft, starting devices located on said support comprising gears, and a housing for said gears integrally formed with said support.

2. In a system of the character described, the combination with an automobile engine and its crank shaft, of a main support, said support being provided with points of attachment corresponding to established points of attachment in relation to said engine and its crank shaft, starting devices located on said support comprising gears, a housing for said gears integrally formed with said support, and an integrally formed timing gear housing on said support.

3. In a system of the character described, the combination with an automobile engine and its crank shaft, of a main support, said support being provided with points of attachment corresponding to established points of attachment in relation to said engine and its crank shaft, starting devices located on said support comprising gears, a housing for said gears integrally formed with said support, a second integrally formed housing on said support for timing gears, and an integrally formed oil receptacle on said support.

4. In a system of the character described, the combination, with an automobile engine

and its crank shaft, of a support provided with points of attachment corresponding to originally established points of attachment on said engine for a gear cover and water coupling, a starting motor, a generator and a fan located on said bracket, driving devices for the crank shaft, generator and fan also on said bracket, and a timer hous-

ing and water coupling also formed on said support.

In testimony where I have hereunto set my hand this 25th day of February, 1916.

JOHN O. HEINZE.
